FIG. 2

INVENTOR -

Oscar Woodwell

By Jacob Felbel

HIS ATTORNEY

UNITED STATES PATENT OFFICE.

OSCAR WOODWARD, OF NEW YORK, N. Y., ASSIGNOR TO WYCKOFF, SEAMANS & BENEDICT, OF ILION, NEW YORK, A CORPORATION OF NEW YORK.

TYPE-WRITING MACHINE.

No. 857,706.

Specification of Letters Patent.

Patented June 25, 1907.

Application filed September 30, 1905. Serial No. 280,858.

To all whom it may concern:

Be it known that I, OSCAR WOODWARD, a citizen of the United States, and a resident of the borough of Manhattan, city of New York, in the county of New York and State of New York, have invented certain new and useful Improvements in Type-Writing Machines, of which the following is a specification.

This invention relates to tabulating mechanisms of writing machines and more particularly to that class of tabulating mechanisms in which a series of denomination keys are employed, each of said keys controlling a denomination stop, said denomination stop being projected by its key and the paper carriage being automatically released by said key and permitted to run freely under the tension of the usual carriage spring until arrested by said projected stop at a point where the writing of a number having the denomination of the operated key may be begun.

The main object of my invention is to provide a novel construction of the carriage releasing mechanism in connection with a tabulator of the class described.

In the accompanying drawings, Figure 1 is a top plan view of so much of a type-writing machine as is necessary to a correct understanding of my invention, some of the parts being broken away and other parts being shown in section. Fig. 2 is a side elevation of the machine, some parts being shown in section and other parts being omitted and broken away.

In the drawings, the frame of the machine comprises a base 1, corner posts 2 and a top plate 3. Key levers 4 are fulcrumed at 5 in the rear of the base, each of said key levers being provided with a restoring spring 6 and being connected by a link 7 with a type bar 8, the latter being pivoted at 9 in a hanger 10 secured to the top plate. The hangers are circularly arranged so that the type bars mounted therein may strike at a common printing point on the under side of a platen 11 mounted in a platen carriage 12, the latter being provided at the front and rear with rollers 13 and 14, which run upon parallel guide rails 15 and 16. A carriage rack 17 is secured to curved supporting arms 18 pivoted at 19 at the rear of the carriage 12, and said carriage rack normally meshes with a feed pinion 20, which latter is operatively

connected to an escapement wheel 21 controlled by a feed dog 22 and a holding dog 23, both of said dogs being carried upon the upper end of a dog rocker 24 pivoted at 25 to a fixed part of the machine. The dog rocker has secured to it forwardly extending arms 26 connected by hooked members 27 with a universal bar 28 which extends from side to side of the machine beneath the series of key levers; but only one arm 26 and one hooked member 27 appear in the drawings. When the key levers are actuated to cause the type bars to print, the universal bar 28 through the connections described vibrates the dog rocker 24, causing the escapement members or dogs 22 and 23 to co-operate in a known manner with the escapement wheel 21 to permit the platen carriage to be drawn leftward a letter space distance under the influence of a spring drum 29 with which said carriage is connected by a strap or band 30 which engages a hook 31 secured to the carriage. The structure thus far described is essentially the same as that of the well known No. 6 Remington typewriter and it is therefore not considered necessary to describe the parts in greater detail.

One or more column stops 32 are disposed along a column-stop rack-bar 33 which extends parallel with the platen 11 and is suitably secured upon the ends of arms 34 projecting rearwardly from a bar 35, the latter having downwardly extending ears 36 which are suitably secured to the axles of the rear rollers 14 of the platen carriage. Denomination stops 37 are arranged at letter space intervals apart and sufficiently in the rear of the column-stop rack-bar 33 to normally clear the column stops 32, said denomination stops 37 being formed at the upper ends of vertically disposed levers 38 pivoted on a fulcrum rod 39 and connected at their lower ends with horizontally disposed push rods 40, the latter extending forwardly beneath the base 1 and carrying at their front ends keys 42. The fulcrum rod 39 is supported at its ends in a vertically arranged frame or bracket 43, said bracket being clamped to the base of the machine by set screws 44 (one only of the latter being shown) and being connected near its upper end by a screw 45 with a U-shaped supporting member 46, which member is in turn supported at the

ends of a guide rod 47 common to the Remington machine. The push rods 40 fan outwardly or laterally as they approach the front of the machine and each of said push rods is provided with the usual restoring spring 49 and has its bearings in a longitudinally disposed supporting bracket 50 which is clamped to the bottom portion of the front of the machine base. The tabulating mechanism as thus far described is generally similar to the well-known Gorin tabulator, and for the purposes of my invention it is not deemed necessary to here describe the parts in greater detail.

Above the fulcrum rod 39 the supporting frame or bracket 43 is formed with a forwardly and upwardly projecting portion 51 which is provided with vertical kerfs or slots 52. Each slot 52 receives a bell crank lever 53 fulcrumed on a fulcrum rod 54 which extends from side to side of the part 51. The number of bell crank levers 53 corresponds to the number of denomination stops, which number is ten in the particular tabulator illustrated herein; but the number of denomination stops employed is immaterial. The upwardly extending arm of each of the ten bell cranks 53 is formed with a slot 55. Engaging said slot is a pin 56 secured to and extending laterally from a short ear 57 integral with the associate denomination stop lever 38. The forwardly extending and horizontally disposed arms of the bell-crank levers 53 are off-set laterally as appears in Fig. 1, five of said bell crank arms or half the entire number being bent or offset to the left of the escapement wheel 21 and the remaining half being bent to the right of said wheel. The forward end of each horizontally disposed bell crank arm is bifurcated as indicated at 58, the bifurcated portion engaging with a pin 59 projecting laterally from the rear end of a lifting lever 60. There are ten of these lifting levers, one for each bell crank, and they are divided into two groups, one group comprising five of the levers being arranged at the left of the escapement wheel 21 and its bearing and the other five levers being arranged at the right thereof. Beginning at the rear end the levers of each group first bend laterally outward, these lateral bends 60^a being succeeded by portions 60^b extending straight toward the front of the machine, the portions 60^b being followed in turn by portions 60^c which bend inwardly toward the center of the machine. The forward end of each lever 60 is formed with a horizontally arranged lip or lifting shoe 61 which normally stands beneath and out of contact with the carriage rack 17. As appears in Fig. 1, the two groups of lifting shoes 61 are arranged so that the members composing each group are close together, the innermost member of each group being but a short distance from

the feed pinion 20. Bearing brackets 62 and 63 are similarly secured by headed screws 64 to the top plate of the machine, each bearing bracket being slotted or kerfed to receive the portion 60^b of all the lifting levers 60 save the innermost lever of each group. The levers 60 move freely in their slots in the bearing brackets and are pivoted on short fulcrum rods 65. The inner end of each fulcrum rod 65 is provided with a fixed collar 66 abutting the inner lifting lever 60 of the group, said inner lever being arranged between the collar 66 and the end of the bearing bracket. The outer end of each rod 65 is threaded to receive a nut 67 which assists in retaining the rod in place.

When it is desired to operate the tabulating mechanism the proper denomination key 42 is pushed in, thereby actuating the associate lever 38, the lever arm of said lever being swung rearwardly about the fulcrum 39 and the upper arm of said lever being swung forwardly about said fulcrum, the associate denomination stop 37 being thereby moved forward to operative position. As the upper arm of the lever 38 moves forward it actuates the associate bell crank lever 53 through the pin and slot connection 55—56, swinging the horizontally disposed arm of the bell crank lever downwardly about the fulcrum 54, said horizontally disposed arm in turn acting on the associate lifting lever 60 to swing the rear arm of said lever downward about the fulcrum 65 and the forward arm of said lever upward about said fulcrum. As the forward arm of the lifting lever is swung upward the lip or shoe 61 at its end contacts with the carriage rack 17 and swings the latter upward about the pivots 19 until said rack disengages from the pinion 20. As soon as the rack is separated from the pinion, the carriage 12, freed or released from the escapement devices, is drawn leftward across the top plate by the spring drum 29, this free movement of the carriage continuing until the column stop 32 coacts with the projected denomination stop 37. The key 42 is therupon released and the parts of the tabulating mechanism actuated by said key are restored to normal position by the spring 49, while the rack 17 is caused to re-engage with the pinion by the usual rack spring (not shown). The desired characters may then be printed in a known manner and thereafter the tabulating mechanism may be again operated in the manner described to release or free the carriage from its escapement devices and permit said carriage to be drawn freely leftward until the next column stop coacts with the projected denomination stop.

It will be observed that by my construction I provide a series of denomination keys, each of said keys being adapted to operate an associate denomination stop member and also to operate an associate device for releas-

ing the carriage of the machine from the escapement devices; that each of said releasing devices is separate from all the other releasing devices and is operated by the 5 nomination key with which it is associated independently of all the other releasing devices.

While I have shown my invention as embodied in the tabulating mechanism commonly known as the Gorin tabulator and as applied to the No. 6 Remington typewriting machine, it is to be understood that said invention may be adapted to other styles of tabulating mechanisms and writing machines, and that various changes in the construction and in the arrangement of the parts may be effected without departing from the spirit of the invention.

What I claim as new and desire to secure 20 by Letters Patent, is:—

1. In a typewriting machine and in a tabulating mechanism, the combination of a carriage; escapement devices; a column stop; a series of key-actuated denomination stop 25 members; and a series of releasing devices each of said series of releasing devices being adapted to be actuated by one of said series of denomination stop members to release said carriage from the escapement devices and 30 permit it to run freely until the actuated denomination stop member and said column stop coact.

2. In a typewriting machine and in a tabulating mechanism, the combination of a carriage; escapement devices; a column stop; a series of key operated denomination stop members; and a series of independently operable releasing devices each of which is adapted to be operated by one of said series 40 of denomination stop members to release said carriage from the escapement devices and permit it to run freely until the operated denomination stop member and the column stop coact.

45 3. In a typewriting machine and in a tabulating mechanism, the combination of a carriage; escapement devices; a column stop; a series of key operated denomination stop members; and a series of releasing devices 50 each separate from the others and operable by one of said denomination stop members to release said carriage from the escapement devices.

4. In a typewriting machine and in a tabulating mechanism, the combination of a carriage; a column stop; a series of pivoted denomination stops; a series of actuating keys therefor; and a series of devices for releasing said carriage, each device being operable by 60 one of said keys and independently of all the other releasing devices.

5. In a typewriting machine and in a tabulating mechanism, the combination of a carriage; escapement devices; a column stop; a series of keys; a series of denomination stop

members operable by said keys; and a series of releasing devices also operable by said keys and adapted to release the carriage from its escapement devices, each key and its associate denomination stop and releasing device being operable independently of all the other keys, denomination stops and releasing devices.

6. In a typewriting machine and in a tabulating mechanism, the combination of a carriage; escapement devices including a rack and pinion; a column stop; a series of keys; a series of denomination stops operable by said keys; and a series of independently movable levers each operable by one of said keys 80 to separate said rack and pinion.

7. In a typewriting machine and in a tabulating mechanism, the combination of a carriage; escapement devices including a rack and pinion; a column stop; a series of keys; a series of denomination stops operable by said keys, a series of levers; and connections between said levers and said denomination stops, each of said levers being operable independently of all the other levers to separate 90 said rack and pinion and permit the carriage to move freely until it coacts with the operated denomination stop member.

8. In a typewriting machine and in a tabulating mechanism, the combination of a carriage; escapement devices including a rack and pinion; a column stop; a series of push rods; denomination keys thereon; a series of pivoted denomination stops, each connected with one of said push rods; a series of bell 100 crank levers, each connected with one of said denomination stops; and a series of lifting levers, each adapted to lift said rack from said pinion and each connected with one of said bell crank levers.

105 9. In a typewriting machine and in a tabulating mechanism, the combination of a carriage; escapement devices including a rack and pinion; a column stop; a series of push rods; denomination keys at the front of the 110 machine and connected with said push rods; a series of pivoted denomination stops, each operable by one of said push rods; a series of bell crank levers; pin and slot connection between each of said bell crank levers and one 115 of said denomination stops, and a series of levers provided with lifting shoes, each of said levers being connected with one of said bell crank levers and operable by the latter to lift said rack out of engagement with said 120 pinion.

10. In a typewriting machine and in a tabulating mechanism, the combination of a carriage; escapement devices; a column stop, a supporting frame detachable from the machine; a series of key actuated denomination stop members fulcrumed in said frame; a series of devices connected with said stop members and each associated with a denomination stop member and each operable inde- 125 130

pendently of the other releasing devices to release the carriage during the tabulating operation.

11. In a typewriting machine and in a tabulating mechanism, the combination of a carriage; escapement devices; a column stop; a series of key actuated denomination stop members; a series of devices, each associated with a denomination stop member and each operable independently of the other releasing devices to release the carriage during the tabulating operation.

12. In a typewriting machine and in a tabulating mechanism, the combination of a carriage; escapement devices including a rack and pinion; a column stop adjustably mounted on said carriage; a series of spring pressed push rods mounted beneath the machine base and each provided with a finger key; a detachable frame or bracket mounted on the frame of the machine; a series of denomination stop members fulcrumed in said bracket and each connected with one of said push rods; a series of bell crank levers fulcrumed in said bracket, and each connected with one of said denomination stop members; a series of levers each connected with one of said bell crank levers at one end, and each having a lifting shoe at the other end adapted to co-act with said rack to lift it out of engagement with said pinion.

13. In a typewriting machine and in a tabu-

lating mechanism, the combination of a carriage; escapement devices; a set of column stops; a series of key-actuated denomination stop members; and a series of releasing devices, each of said series of releasing devices being adapted to be actuated by one of said series of denomination stop members to release said carriage from the escapement devices and permit it to run freely until the actuated denomination stop member and one of said column stops co-act.

14. In a typewriting machine and in a tabulating mechanism, the combination of a carriage; escapement devices; a set of column stops; a series of key-operated denomination stop members; and a series of releasing devices, each operative by one of said denomination stop members, said releasing devices being separately adjustable, each being adapted to be set or timed to effect the release of said carriage from the escapement devices independently of the operation of any of the other denomination stop members and releasing devices.

Signed at the borough of Manhattan, city of New York, in the county of New York, and State of New York, this 28th day of September, A. D. 1905.

OSCAR WOODWARD.
